United States Patent Office

Des. 229,553

Patented Dec. 11, 1973

229,553

ARTICULATED ALL TERRAIN VEHICLE

Henry A. Ford, San Jose, and David R. Fleming and James F. King, Cupertino, Calif., assignors to Lockheed Aircraft Corporation, Burbank, Calif.

Filed Aug. 11, 1971, Ser. No. 171,044

Term of patent 14 years

Int. Cl. D12—09, 10

U.S. Cl. D14—3 J

FIG. 1

FIG. 2

FIG. 3

FIG. 4

FIG. 5

FIG. 1 is a perspective view of an articulated all terrain vehicle showing our new design,

FIG. 2 is a front elevational view,

FIG. 3 is a left side elevational view, the right side being substantially a mirror image thereof,

FIG. 4 is a top plan view, and

FIG. 5 is a rear elevational view.

We claim:

The ornamental design for an articulated all terrain vehicle, as shown and described.
